CONVERTER

Walter L. Kerlie, Monroeville, Pa., assignor to United States Steel Corporation, a corporation of New Jersey

Application June 28, 1956, Serial No. 594,585

2 Claims. (Cl. 266—35)

This invention relates to a surface blown converter for refining pig iron which is especially adapted to the practice of a surface blowing process for making steel of open hearth quality as disclosed in my copending application Serial No. 588,762 filed June 1, 1956.

The process of my said copending application provides improvements over the surface blowing process disclosed in United States Patent No. 2,733,141 to Clarence E. Sims which are directed to the end among others of obtaining improved circulation of the slag and metal at the surface of the bath and thereby a reduction of wear or erosion of the refractory converter lining as well as a more efficient refining operation. The process disclosed in the Sims patent requires an air blast which is directed against the surface of the bath at a velocity and angle of incidence such that a surging non-circulating wall of foaming slag may be formed in front of the tuyeres and against the side of the vessel opposite the tuyeres. This non-circulating wall of foaming slag has been known to obstruct the blast from the tuyeres and to cause a "throw-back" of slag and metal, which erodes the refractory lining particularly in the area about the tuyeres. The formation of this surging wall of foaming slag is prevented and an improved continuous circulation of slag and metal at the surface of the bath is obtained, according to the disclosure of my copending application, by confining the blast to an area centrally of the ends of the bath and in such manner that the slag and metal which is moved across the surface of the bath by the blast will circulate from the area in front of the tuyeres through the areas at the ends of the bath and thus be continuously circulated or returned to a position for further movement by the blast over the surface of the bath. This circulation of the slag and metal at the surface of the bath is assisted by conducting the blowing operation in a barrel-shaped converter which is supported in a horizontal position so that its sides provide a cover for the bath and which has its mouth opening outwardly from an end thereof and spaced from the area over the bath.

One of the principal objects of this invention is to provide an apparatus which is particularly adapted for practicing the processes of the above mentioned Sims patent and copending application and which will further improve the circulation of slag and metal at the surface of the bath.

Another object of the invention is to provide an apparatus for converting iron to steel by surface blowing which is particularly adapted to an operation using oxygen or oxygen-enriched air as an oxidizing blast.

A further object of the invention is to provide a surface blown converter in which an oxidizing blast is applied to the surface of the bath through a plurality of water-cooled tuyeres which are arranged in a horizontal row and respectively project through a side of the converter at an angle such that each tuyere axis forms an acute angle with the surface of the bath and intersects such surface at a point spaced from the said side of the

2

converter. Incidental to this object, another object of the invention is to provide a space in back of the points of impingement of the tuyere blasts with the bath surface into which slag and metal may circulate from both ends 5 of the bath as a part of a continuous recirculating movement.

Other objects and advantages will become apparent from the following description.

In the drawings there is shown a preferred embodiment 10 of the invention. In this showing:

Figure 1 is a side elevation of the converter of this invention;

Figure 2 is a sectional view taken substantially in the plane of the line II—II of Figure 1;

Figures 3 and 4 respectively are sectional views taken substantially in the planes of the lines III—III of Figure 2 and IV—IV of Figure 1; and

Figure 5 is an enlarged sectional view taken axially of 20 one of the water-cooled tuyeres shown in Figures 2 through 4.

The converter of this invention comprises a vessel 1 which is shown in the drawings as having a cylindrical or barrel shape. It has a metal shell 2 with a refractory lining 3 in the manner of conventionally fabricated converters and is mounted for rotation with its axis in a horizontal position. Its mounting includes a pair of axially spaced rocker rails or wheels 4 which are secured to the shell 2 concentrically with respect to the axis of the vessel 1 and have rolling engagement on supporting rollers 5. A sprocket or gear drive (not shown) is provided for tilting the vessel 1 to and from its upright blowing position as shown in the drawings.

The inner end of the vessel 1 is closed by a manhole cover which includes a mounting plate 6 and a preformed and tapered dolomite block 7 which are detachably secured to the shell 2. The provision of a removable manhole in this manner enables replacement of the refractory lining 3 according to the practice used in relining standard basic Bessemer converters. For relining in this manner, the plate 6 is removed and the vessel 1 is placed in an upright position after removal from its supporting rollers 5. After the lining 3 has been replaced, the tapered block 7 is rammed into position and the plate 6 is detachably fastened to the shell 2.

A wind-box or manifold 10, shown somewhat diagrammatically in Figures 1 through 4 of the drawings, extends between the rocker wheels 4 and is supplied with oxygen, air, or oxygen-enriched air from a coupling 11 which is connected to the manifold 10 by a conduit 12. The coupling 11 is removably secured to the shell 2 about the plate 6 and is connected to an air supply conduit 13 which is rotatably supported in suitable bearings (not shown).

At its outer end the converter has a nose section 15 which is shaped to provide a mouth 16 in a skewed and eccentric position with respect to the axis of the converter as best shown in Figure 3. When the vessel is in its operative blowing position as shown in the drawings, its

mouth 16 is arranged at one side of the area directly over the bath and faces outwardly in an endwise direction from the vessel. The mouth 16 has its lower edge 17 located well above the surface 18 of the converter bath and its upper edge 19 is flush with the top of the lining 3 which provides a cover over the bath. From the lower edge 17, the lining surface slopes downwardly at an angle of approximately 45° as shown in Figure 3. The shape of the nose 15 and the skewed location of the mouth 16 are effective in preventing ejection of metal and slag from the vessel by splashing. To tap slag or metal it is only necessary to rotate the vessel in a counterclockwise direction as viewed in Figure 2 to lower the mouth 16 to

a position below the level of a bath in the converter. The mouth 16 preferably has a large diameter providing for visual inspection of the lining and such fettling repairs thereto as may be needed. The provision of a wide mouth 16 in a relatively short nose section 15 results in a relatively low velocity of the spirally moving waste gas emerging from the vessel. In this manner, deposition of slag and metal in the upper portion of the nose 15 is kept at a minimum and skulling of the mouth 16 is eliminated.

The manifold 10 extends horizontally between the rocker rails 4 and has connections of a character to be described with a plurality of water-cooled tuyeres which are respectively designated as a whole by the numeral 20 and are shown somewhat diagrammatically in Figures 2 through 4. The tuyeres 20 are arranged in a horizontal row in positions parallel to each other and with their axes extending transversely of the axis of the vessel 1 and intersecting with the surface 18 of the converter bath at an acute angle. The inner ends 22 of the tuyeres 20 are spaced from the converter side 23 through which the tuyeres project and are positioned over the surface 18 of the converter bath. The axes of the tuyeres 20 form an acute angle with the surface of the bath which should be kept between 5° and 45°, preferably an angle of about 25°-30° as shown in Figure 2. In this manner, such axes intersect with the surface 18 at points which are arranged along the broken line designated by the numeral 24 in Figure 4 of the drawings. The angular inclination of the tuyeres 20 thus provides space 25 along the side 23 of the vessel into which slag and metal may circulate in a manner to be described.

As explained in my above mentioned copending application, the tuyeres 20 have a minimum spacing relative to each other which is determined by the tuyere diameter and the velocity of the air or oxidizing gas in feet per second moving therethrough. This minimum tuyere spacing is given by the empirical equation

$$S = 2.5D^2V^2/10^6$$

wherein S is a tuyere spacing in inches, D is the tuyere diameter in inches, and V is the wind velocity in feet per second. In addition, the end tuyeres 20 have a spacing from the end of the vessel such that the end portions 26 of the bath 18 respectively have an axial length outwardly of the end tuyeres 20 of about

$$27 + \frac{S}{2} \text{ inches}$$

The spacing of the end tuyeres 20 in this manner provides for return circulation of slag and metal over the surface of the bath and a more effective slag circulation and mixing of the metal and slag forming constituents.

By reason of the vessel side 23 being flattened as shown in Figure 2, and the barrel shape of the vessel 1 as shown in Figures 2 and 3, the periphery of the bath in the vessel will have a D-shaped contour as designated by the broken line 27 in Figure 4 with its flat side located along the vessel side 23. The blast from the tuyeres 20 is effective to move the slag and metal at the surface of the bath transversely of the vessel axis over the space 28 between the end zones 26. By reason of the curvature of the vessel side opposite the tuyeres 20 and the fact that the end zones 26 of the bath are not subjected directly to blast from the tuyeres, slag and metal at the surface of the bath will circulate in opposite directions from the center space 28 into both of the end zones 26. By reason of the angular position of the tuyeres 20 above the surface of the bath and the fact that the axes of the blasts therefrom impinge with the bath surface along the line 24, the slag

and metal moving into the end zones 26 may circulate freely into the space 25 between the line 24 and vessel side 23. The slag and metal moving into the space 25 in this manner moves into the path of the blast from the tuyeres 20 so that it circulates continuously over the surface of the bath.

As best shown in Figure 5, each of the tuyeres 20 comprises a hollow pipe 30 having its inner end connected with the manifold 10. A tubular jacket 31 about the pipe 30 and a tubular partition 32 form an enclosure about the pipe 30. A water supply conduit 33 delivers cooling water to the interior of the partition 32 where it is constrained to flow downwardly over the surface of the pipe 30. The lower end of the partition 32 is spaced from the end 34 of the jacket for the pipe 30 so that the cooling water is circulated upwardly through the space 35 to the upper end of the jacket 31. The upper end of the jacket 31 is connected with an exhaust conduit 36 for the cooling water.

Each of the tuyeres 20 extends through an opening 37 which extends through the shell 2 and a preformed refractory block 38 which is rammed in an opening in the lining 3. Flanges 39 and 40 respectively on the tuyeres 20 and a mounting member 41 welded to the shell 2 are connected together to secure the tuyeres 20 in position.

While one embodiment of my invention has been shown and described it will be apparent that other adaptations and modifications may be made without departing from the scope of the following claims.

I claim:

1. A surface blown converter comprising a refractory lined vessel for containing a bath of slag and metal, means mounting said vessel in a horizontal position for rotational movement about its longitudinal axis, said vessel providing a cover over the bath in its bottom portion and having a mouth opening outwardly from one end thereof in an eccentric position relative to said axis, a wind box extending horizontally along one side of said vessel, a horizontal row of water-cooled tuyeres respectively extending through said vessel side and having their outer ends connected with said wind box and their inner ends positioned over the bath in said vessel and spaced from said vessel side, the tuyeres at opposite ends of said row being spaced inwardly of the ends of said bath, each of said tuyeres extending transversely of said bath and having a downward angular inclination relative to the surface thereof whereby its axis intersects with said bath surface at an acute angle and at a point spaced from said vessel side to provide for circulation of slag and metal from both of said bath ends into the space between said vessel side and said points.

2. A converter as defined in claim 1 characterized by said vessel having a barrel shape and being flattened along said one side such that its said lower bath containing portion has a D-shaped contour in a horizontal plane and a bath contained therein has a similarly shaped contour.
